UNITED STATES PATENT OFFICE.

HANS N. HALVESEN, OF VINELAND, NEW JERSEY, ASSIGNOR TO KIMBLE GLASS COMPANY, OF CHICAGO, ILLINOIS, A CORPORATION OF ILLINOIS.

SCREW-NECK-FORMING MACHINE.

Application filed December 13, 1919. Serial No. 344,618.

To all whom it may concern:

Be it known that I, HANS N. HALVESEN, a citizen of the United States, residing at Vineland, in the county of Cumberland and 5 State of New Jersey, have invented certain new and useful Improvements in Screw-Neck-Forming Machines, of which the following is a specification.

The prime purpose and leading aim of the 10 present invention is the provision of an appliance for providing glass bodies, such as vials or bottles, with screw-threaded necks by means of which tops or closures may be maintained thereon. A salient feature 15 of the invention is the production of an automatic machine of relatively few and simple parts for performing this work with accuracy and speed, requiring nothing more than a minimum amount of attention on 20 the part of the operator or workman.

In order that those skilled in this art may understand how these and other desirable objects and aims are fulfilled in a machine incorporating this invention, I have illustrated 25 a preferred embodiment of the same in the accompanying drawings forming a part of this specification, which should be considered in connection with the following detailed description of the device, and 30 throughout the various views of which like reference numerals refer to the same parts of the mechanism.

In these drawings:

Figure 1 is an elevation of the machine 35 with parts removed to more clearly show the construction;

Figure 2 is an elevation of the left-hand end of the machine;

Figure 3 is an enlarged elevation of a 40 portion of the necking mechanism showing its relation to the vial undergoing heat treatment;

Figure 4 is a view at right-angles to that of Figure 3; and

Figures 5 and 6 are detail sections, Figure 5 being a section on line 5—5 of Figure 6.

Referring to these drawings, it will be seen that the apparatus comprises an up- 50 right hollow standard 10 carrying all of the parts of the mechanism, the partially-

formed glass-vials 11, 11, which are to be provided with screw-threaded necks being delivered individually or one by one from any suitable form of supply-magazine 12 through 55 an intermittently-rotated conveyor 13 on a hollow-shaft 14. The conveyor may be of any appropriate form or construction such as two spaced discs 15 and 16 with aligned seats or notches 17 for the 60 vials, conveyors of this type and their operating mechanism being well known in the art and, therefore, being shown only in part, but sufficiently, however, for a full understanding of the construction and mode of 65 operation of the remainder of the mechanism in which the invention more particularly resides. When the vials reach their uppermost position on the conveyor they rest on suitably-supported anti-friction rollers 70 18, 18 instead of upon the seat 17 of the conveyor. Adjacent to one end of such vials is a curved gauge or guide element 19 75 adjustably held in position by a supporting-arm 20 mounted in any approved manner as, for instance, on a stationary shaft 21 extended through the hollow shaft 14 on which the conveyor proper is mounted.

The uppermost vial 113 on the conveyor resting 80 on the anti-friction rollers 18 is revolved by one or more beveled soft-rubber rollers 22, of which two are shown in the drawings. The deflection or yielding of the rubber at its point of contact with the vial tending to hold or push the latter to the 85 left, as the parts are viewed in Figure 1, against the guide or gauge 19. If desired, the axis of these rubber-rollers may be oblique to that of the vial to assist in holding the latter against the gauge or guide. 90 These rubber drive-rollers are mounted between confining discs 23 and 24 on a revoluble shaft 25 rotatable in a bearing 26 of an arm 27 mounted on and adapted to rock about an intermediate shaft 28 revoluble in a bearing 29 of the main-frame 10. Shaft 28 drives a shaft 25 by means of intermeshing gears 30 and 31 and is in turn revolved by a third shaft 32 rotatably 95 mounted in suitable bearings 33 by means of 100 co-operating gears 34 and 35. Shaft 32 is driven by means of intermeshing bevel-

gears 36 and 37 the latter being mounted on the upper end of an upright shaft 38 rotatable in bearings 39 and 40 outstanding from the main-frame and revolved by a 5 pulley 42 loose on a shaft 41 and co-acting belt 43 through a spur-gear 44 rigid with the pulley which meshes with a larger gear 45 fixed to a lower jack-shaft 46 equipped at one end with a bevel-gear 47 meshing with 10 a similar horizontal bevel-gear 48 rigid with the shaft 38 just above the lower bearing 40.

After the tube or vial 11 has been carried upwardly by the conveyor and deposited on 15 the anti-friction rollers 18, 18, and while it is revolved by the rubber-rollers 22 one or more gas flames 50 from one or more gas burners 51 is automatically caused to play upon the end portion of the vial remote 20 from the guide 19 against which its closed or bottom end bears and when it has become sufficiently heated the necking operation is performed.

The necking mechanism comprises a 25 plunger 52 adapted to enter the mouth of the vial and remain therein during forming of the thread upon its outer surface, such plunger having a shoulder 53 adapted to bear against the end of the neck and form 30 it true and smooth. This plunger, as is illustrated in Figure 1, is mounted on a sliding shaft 54 reciprocatory in a bearing 55 in the main-frame, such shaft being slid back and forth by the upwardly-extended 35 arm 56 of a lever fulcrumed at 57 so as to rock on a shaft 58 supported in suitable bearings 59 and 60, the other arm 61 of the lever having a roller 62 traveling in a cam-groove cut in the side of a cam 63 40 fixed on a cam-shaft 64 revolvably mounted in bearings 65, 65 and rotated by a bevel-gear 66 thereon which is in mesh with a similar gear 67 on a sleeve 68 keyed to the shaft 41 and provided with a gear 69 in 45 mesh with a smaller gear 70 fixed to shaft 46. Thus, by means of these co-acting gears the cam-shaft is driven from the belt operated pulley 42 all as will be readily understood.

50 The shape of the groove of cam 63 is such that when the adjacent end of the partly-formed vial 11 has been sufficiently heated or partly fused, the cam will cause the plunger 52 to enter such heated end and 55 remain therein during the neck forming operation, the plunger being retracted subsequently at any suitable time.

The appliance is additionally equipped 60 with a sliding shaft 71 reciprocated toward and from the work by a lever 72 mounted and free to rock on the shaft 58, the lower end of the lever having a roller 73 traveling in the cam-groove of a cam 74 mounted on and rotated by the cam-shaft 64.

65 Rockingly mounted transversely on the

shaft 71 a member 75 is provided, carrying by means of a clamp 76 of suitable design, a shaft or rod 77 equipped with a thread-forming roller 78 revoluble thereon, the pitch-circle of such thread-producing roller 70 being twice the diameter of the pitch-circle of the completed threaded neck of the vial.

This roller 78 has two parallel thread-forming grooves each of a pitch twice that of the thread which it produces on the exterior surface of the neck of the vial. Besides the element 75 shaft 71 is equipped with another similar member 80 having a clamp 81 holding a rod 82 on which is revolvably mounted a neck-forming roller 83, 80 the two elements 78 and 83 being parallel to one another and adapted to approach and recede from one another by reason of the rocking of their supporting members 75 and 80 transversely on the shaft 71.

The two members 75 and 80 are provided with lugs 84 and 85 apertured in alignment, such holes accommodating a threaded screw 86, the head 87 of which is adapted to bear against the upper surface of the extension 90 84. Screw 86 has an adjustable nut 88 between which and the under face of the boss 85 a coil-expansion spring 89 is positioned, the spring encircling the screw as is clearly illustrated. It should be clear, therefore, that this spring tends to yieldingly press the two elements 78 and 83 toward one another, but in order to hold these parts separated, except when it is required that they shall move toward one another, the following instrumentalities are employed. Rock arm 75 has a slotted lateral extension 90, the slot 91 of which accommodates a threaded boss or lug 92 on an adjustable wedge or cam 93, the adjustment of which 105 is secured by a screw 94 extended through and fitting in the threaded aperture of the part 92. The bevel or wedge face of the element 93 co-acts with a bifurcated arm 95 hinged to the member 75 at 96 and carrying at its other end an anti-friction roller 97.

In similar manner the oscillatory member 80 is equipped with an adjustable cam or wedge 98 co-acting with the hinged arm 115 99 carrying an anti-friction roller 100.

It will be apparent that by spreading these two rollers 97 and 98 apart, the two neck-forming elements 83 and 78 may be maintained separated and away from the 120 vial. To the accomplishment of this end an arm 101 with two opposite cam portions 102 and 103 against which the rollers 97 and 100 bear is hinged on a pin or shaft 104 in an arm 105 projecting outwardly from 125 a collar or sleeve 106 on shaft 71. The outer end of the cam lever or arm 101 is pivotally connected by a right-angle connection 107 to the top end of a vertical link 108, the lower end of which is pivoted to an arm 130

109 hinged to the rock-shaft 58 which is oscillated as required to perform the needed movement by an arm 110, the hub of which is keyed to the shaft, and the other end 5 of which carries a roller 111 traveling on the exterior of a properly-shaped cam 112 on cam-shaft 65.

In these drawings the completed necked vial has been supplied with the reference 10 character 113 and the magazine into which the completed articles are delivered or discharged has been furnished with the reference numeral 114.

The operation of the machine occurs practically as follows:

The partly completed vials, such as sections of glass tubes closed at one end, are delivered one by one to the step by step operated conveyor 13 and deposited singly 20 in the seats or cavities thereof. Each tube is in turn brought up to and deposited upon the rollers 18, 18 by the conveyor, and in this position revolved by the beveled rubber discs 22 for a sufficient period of time for 25 the completion of the heating and neck-forming operations. The finished vial is subsequently moved along by the conveyor and delivered into the compartment 114. The conveyor handles several vials at the 30 same time, but only one, the one on the rollers 18, is heated and formed to shape.

If desired, positively acting means may be provided for raising and lowering the rubber-discs 22 and their mountings, but, inasmuch as this conveying and tube or vial rotating means is old in the prior art, it has not been deemed necessary to set it forth more fully in detail. It will be readily understood that any suitable and appropriate 40 feeding and revolving means for the vials may be employed.

As soon as the rotation of the vial on the rollers 18 is instituted by the revolving discs 22 the gas and air for the one or more burners 51 is automatically turned on by means 45 not shown but well understood in this art and the end portion of the vial 11 remote from the guide or gauge 19 is heated and, when it has been subjected sufficiently to 50 such heat, the plunger 52 enters the same and stops with the shoulder 53 in proper position. When the heating has been completed the supply of gas and air is automatically turned off or reduced, as will be readily understood, whereupon the shaft 71 55 advances bringing the two tools or rollers 78 and 83 into proper register with the end part of the vial and at the proper moment the arm 101 is rocked by its actuating cam 60 mechanism to permit the two members 75 and 80 to respond to the action of spring 89 which presses the two rollers 78 and 83 toward one another, thereby forming the reduced threaded neck portion of the vial, as 65 will be readily understood. These two

forming rollers are revolved solely by their contact with the vial and as has been explained above the roller 78, although of twice the pitch diameter of the threaded neck and with parallel grooves of twice the 70 pitch of the thread to be formed on the neck, produces on such neck a single screw thread of the desired diameter, size, and pitch. Thereupon, the arm 101 is rocked so as to separate the rollers 78 and 83 as illustrated 75 in Figure 4 and both shafts 71 and 54 recede carrying all of the tools away from the conveyor and the vials therein. Then the conveyor makes another partial rotation carrying away the necked vial and bringing 80 a new tube section or partially formed vial into place for heating and neck forming.

In this appliance the spirally grooved thread-forming roller is rotated by reason of its contact with the plastic glass neck of 85 the bottle or vial. Obviously, if there is any considerable friction on the forming roller, the plastic glass of the neck is likely to be detrimentally deformed or distorted. It is desirable or essential, therefore, that the 90 thread forming roller should be revolvable with as little friction as possible, and accordingly it is made of considerably larger diameter than the neck for the reduction of 95 such friction. Since some vial necks are quite small, it would require a very small forming roller to put the thread on the neck if such forming roller were to be of the same diameter as the neck, and this would lead to difficulty in providing suitable ball bearings 100 for such roller because of their necessary small size. In other words, by making the thread forming roller larger, better and more efficient ball bearings can be employed with less resulting friction. The larger the forming roller the more readily it is turned by 105 the vial neck, and hence by having it, for example, twice the diameter of the neck, practically only one-half of the torque is 110 required to revolve it.

The appliance shown and described as incorporating the elements of this invention may be modified or varied in mechanical details to a large extent without departing from the substance and essence of the invention and without the sacrifice of any of its essential benefits and advantages, and accordingly the appended claims are to be construed as broadly as permissible by the state of the prior art.

I claim:

1. In a screw-necking machine of the character described, the combination of means to revolve the body to be necked, means to heat the part of the body to be necked, a 125 revolvably-mounted roller having a plurality of parallel thread-forming spiral-grooves of a pitch circle diameter different from that of the threaded neck produced, and means to operate said roller transverse- 130

ly of its axis toward and from the work, substantially as described.

2. In a screw-necking machine of the character described, the combination of 5 means to revolve the body to be necked, means to heat the part of the body to be necked, a revolubly-mounted roller having a

plurality of parallel thread-forming spiral-grooves of a pitch circle diameter and of a pitch different from those of the threaded necks produced, and means to operate said roller transversely of its axis toward and from the work, substantially as described. 10

HANS N. HALVERSEN.
